VEST

Filed April 17, 1926

INVENTOR
R. E. Davis,

BY *Maurice H. Lee*

ATTORNEYS

UNITED STATES PATENT OFFICE.

ROBERT EVAN DAVIS, OF FORT PAYNE, ALABAMA.

VEST.

Application filed April 17, 1926. Serial No. 102,775.

My invention relates to improvements in men's vests, and it consists in the combinations, constructions and arrangements herein described and claimed.

5 An object of the invention is the provision of a vest having a body which will conform to the body of a wearer at all times, and will yield in response to muscular movements of the body of the wearer without discomfort to the wearer of the vest.

10 A further object of the invention is the provision of a vest which is circumferentially expandible for part of its length so as to permit bending or twisting of the body 15 of the wearer without impairment of the fit of the vest and without discomfort to the wearer.

Other objects and advantages of the invention will be apparent from the following description, considered in conjunction with the 20 accompanying drawings, in which—

Figure 1 is a perspective view of the improved vest in applied position on the body of a wearer, showing the back of the vest.

25 Figure 2 is a relatively enlarged fragmentary horizontal section through the joined together lapped edge portions of an elastic insert or goring and the inelastic body of the vest, the view being substantially along 30 the line 2—2 of Figure 1.

In carrying out the invention, I make use of a vest having a body 1 of generally conventional construction and form. This body 1 may include a lining 1^a of any suitable 35 fabric and a cover 1^b, as shown in Figure 2. The fabrics of which the lining and the cover members of the body of the vest are formed are inelastic, as is usual. The body 1 of the vest differs from the conventional in 40 that it is provided with a substantially inverted V-shaped notch or cut-away portion at 2 which extends from the lower edge of the back of the vest along the vertical median portion of the back of the vest substantially to the level of the bottom of the 45 arm openings 3 of the vest body. The apex of this cut-away portion 2 of the vest body is at the top so that the side walls of the cut-away portion 2 are inclined toward each 50 other from their lower ends to their upper ends and thus extend at an oblique angle to the vertical median line of the back of the vest body. An insert or goring 3 of elastic 55 webbing or other suitable elastic material conforms substantially in configuration to the space that is defined by the cut-away

portion 2 of the body of the vest but is slightly greater in width so that the side edge portions of the goring 3, as at 3^a, may be extended between the cover and the lining 60 members of the vest body at the sides of the cut-away portion 2 as shown in Figure 2, the elastic portions of the goring and lining and cover members of the vest body being secured together, as by means of the stitching 65 4.

The vest body may be provided with the usual straps, as at 5 and 6, respectively. These straps respectively are secured to the lower portion of the back of the vest body 70 at opposite sides of the cut-away portion 2 and one of the straps, as the strap 6, is provided at its free end with a buckle 7, which is adjustably engageable with the strap 5.

From the foregoing description of the various parts of the device, the operation thereof may be readily understood. The straps 5 and 6 may be connected together so as to limit the circumferential expansion of the lower portion of the vest body. The 80 lower portion of the vest body then will be permitted to expand in a generally circumferential direction below this limit in response to muscular movements or bending of the body of the wearer of the vest and 85 the vest body will snugly fit the body of the wearer, irrespective of the position of the body of the wearer. Since the insert or goring 3 is substantially triangular with the apex thereof turned upward and the lines 90 of junction of the goring with the side edges of the cut-away portion at 2 in the vest body extend obliquely to the vertical median line of the back of the vest body, it is obvious that movements of the arms of the body of 95 the wearer, as for example when one arm of the wearer is raised above the level of the other arm of the wearer, will be permitted without causing any binding action 100 of the lower portion of the body of the vest on the body of the wearer.

Obviously, the invention is susceptible of embodiment in forms other than that which is illustrated in the accompanying drawings, and I therefore consider as my own all such 105 modifications and adaptations thereof as fairly fall within the scope of the appended claim.

I claim:—

A vest comprising a body made of inelastic material and having a back comprising superposed lining and cover members,

said back having an inverted V-shaped cut-away portion extending from its lower edge at the vertical median portion of the back of the vest body to substantially the level of the bottoms of the arm openings of the vest body, said cut-away portion decreasing regularly in width from its lower end to its top, a strip of elastic material extending between the sides of said cut-away portion and having side edge portions extending between the cover and lining members of the vest back

at the side edges of said cut-away portion, and stitching securing the side edge portions of said goring to the adjacent portions of the lining and cover members of the back of the vest body, and adjustable strap sections secured at their one end to the sides of the back of the vest and extending across the elastic gore section, whereby to limit the expansion of the lower back portion of the vest.

ROBERT EVAN DAVIS.
